UNITED STATES PATENT OFFICE.

CHARLES R. OSTEEN, OF PORTLAND, OREGON.

MILK-CAN FILLER.

1,318,581.

Specification of Letters Patent.

Patented Oct. 14, 1919.

Application filed December 21, 1917. Serial No. 208,272.

To all whom it may concern:

Be it known that I, CHARLES R. OSTEEN, a citizen of the United States, residing at Portland, in the county of Multnomah and 5 State of Oregon, have invented certain new and useful Improvements in Milk-Can Fillers, of which the following is a specification.

This invention relates to filling devices and the object of the same is to provide a 10 device that will direct a stream of liquid flowing from a reservoir into a container and also automatically control the flow of the liquid from the reservoir.

Another object of the invention is to provide a device as described provided with a 15 novel form of locking means for the fluid control means.

A still further object of the invention is to provide a device of the kind described 20 that is simple in construction, efficient in operation and consists of the minimum number of parts.

With these and other objects in view, this 25 invention resides in certain novel features of construction, combination, and arrangement of parts, as will be hereinafter more fully described and claimed and shown in the accompanying drawings wherein;—

Figure 1 is a view in side elevation of the 30 improved device;

Fig. 2 is a view in end elevation of the device as shown in Fig. 1;

Fig. 3 is a fragmentary perspective view 35 of a portion of the trough or reservoir showing the cutoff means in connection therewith, and

Fig. 4 is a detail perspective view of the 40 detachable spout for use in connection with the opening in the trough.

Referring to the parts by reference numerals, 10 designates a supporting frame, the ends of which are of an inverted V-shape. Braces 11 are arranged between and secured to the legs of each V-member and the apex of each of the latter secured by a rivet. The legs are extended above the rivet and bent outwardly to provide semi-circular arms to embrace a reservoir 13. Auxiliary brace legs 14 are provided which 45 are secured to the lower of the braces 11 as clearly shown in Figs. 1 and 2. The reservoir 13 is preferably constructed of sheet metal with its margin 15 rolled over a reinforcing wire 16. At suitable intervals in the 50 trough 13 outlet openings are provided one of which is shown in the drawings at 16'.

At one end of the reservoir an overflow opening 17 is provided, which has a projecting flange 18 extending therefrom. A suitable detachable discharge spout 19 may 60 be telescoped on the flange 18 when it is so desired. Suitable discharge spouts 20 are soldered or otherwise attached to the underside of the trough 13 beneath the openings 16' to direct liquid passing therethrough. 65

For each of the openings 16' formed in the trough 13 there is provided an automatic filling means and in that they are all identical in construction the description of one will suffice. Each of these automatic filling 70 means consists of a lever 21 the same being formed of sheet metal bent on its medial line to provide the spaced walls 22. Adjacent each opening 16' a rod 23 is secured having an eye 24 formed at its upper end as clearly 75 indicated in Fig. 2. The eye 24 on each rod is positioned between the spaced walls 22 of the lever 21 and receives a pivot pin 25, the latter being detachably carried by the walls 22. To prevent loss of the pivot pin a 80 chain 26 is attached thereto and secured to the reservoir. A valve rod 27 is pendently carried by the inner end of each lever 21, the latter carrying a substantially frustoconical valve 28, which is adapted to engage 85 the opening 16' to close communication therethrough. Adjacent each of the openings 16' in the trough 13 is a series of pegs 29 that guides the valve 28. A float rod 30 is carried by the outer end of each lever 21, 90 and has a float 31 secured on its lower end. Movable secured on the rod 30 is an improved form of clasp means adapted for engagement with the receptacle to be filled. This clasp comprises a piece of spring wire 95 bent to form a hook 32 at one end, an eye 33 intermediate the end and a receptacle engaging eye 34, the eye 33 encircling the rod 30 to retain the clasp thereon. Suitable eyes 35 are formed on the clasp to give the 100 same more resiliency. This clasp is adapted to engage the ordinary type of milk can as shown in Fig. 1 and by the same the rod 30 is guided in its movement to insure centering of the float in the can. 105

As is obvious, when the liquid passing through the openings 16 and guided by the spout 20 into the can, reaches a predetermined height, the float 31 will move upwardly, thereby moving each valve 28 into 110 its opening 16' and by closing the said opening prevent the flow of liquid therethrough.

- To positively retain each valve 28 in its respective opening, a suitable locking means is provided which consists of a strap 36 looped midway its ends and equipped with 5 a latch 37. The latch consists of a rectangular wire frame which has one of its sides journaled in the looped portion of the strap and the opposite end engaged with the lower margin of the lever 21.
- 10 It is obvious that minor changes may be made in the form and construction of this device, without departing from the material parts of this device. It is, therefore, not wished to confine the invention to the exact 15 form and construction herein described and claimed, but it is wished to include all such as properly comes within the scope claimed.
- What is claimed is;—
1. A filling device including a relatively 20 high frame-work equipped with a superimposed reservoir, said reservoir having a plurality of openings through which its contents is dispensed into subjacent receptacles, float rods pending from the reservoir and having floats fixed on their lower 25

ends which are actuated by the rise of liquid in the receptacles to close the openings of the reservoir, and means lying horizontally across the receptacles and slidably engaged with said float rods to hold the floats 30 centered in the receptacles.

2. A filling device including a reservoir and movable means to prevent the discharge of liquid from said reservoir, means for controlling the movement of said first mentioned means including a rod having a float attached to one end thereof adapted for placement in a receptacle to be filled and a spring guide means for said rod formed from a single strand of wire bent to form 35 a hook at one end thereof, an eye intermediate the end thereof to receive said rod and an eye at the opposite end thereof.

In testimony whereof I affix my signature in presence of two witnesses.

CHARLES R. OSTEEN.
